CLAIM

We claim the design for a customizable luggage identification and personalization handle cover, as shown and described.

DESCRIPTION

FIG. 1 is a front perspective view of the customizable luggage identification and personalization handle cover, in place attached to the handle of a common type of luggage; FIG. 2 is an enlarged side perspective view of the customizable luggage identification and personalization handle cover in place attached to the handle of a common type of luggage; FIG. 3 is an enlarged top view of the customizable luggage identification and personalization handle cover in place attached to the handle of a common type of luggage; FIG. 4 is a greatly enlarged partially exploded bottom view of the customizable luggage identification and personalization handle cover in an expanded position along with the identification and personalization strips detached from the handle cover; and,

FIG. 5 is a greatly enlarged side elevational view of the customizable luggage identification and personalization handle cover in place attached to the handle of a common type of luggage.

The broken line showing of environmental structure in FIGS. 1, 2, 3 and 5 is for illustrative purposes only and forms no part of the claimed design.
